UNITED STATES PATENT OFFICE.

GEORGE LEE ANDERS, OF BOSTON, MASSACHUSETTS.

TELEPHONE-SWITCH.

SPECIFICATION forming part of Letters Patent No. 238,019, dated February 22, 1881.

Application filed March 31, 1879.

To all whom it may concern:

Be it known that I, GEORGE LEE ANDERS, of Boston, in the State of Massachusetts, have invented a new and useful Improvement in 5 Switches for Telephones, of which the following is a specification.

The invention relates to the instrument to which are attached the telephones as well as the signaling mechanism belonging to each of 10 the several stations.

I am aware of the system described in Doolittle's Patent, No. 209,115, for preventing a telephonic message between any two stations from being heard or picked up at any or all of 15 the other stations, and in which the stations in use are disconnected from the others by the act of putting the said two in connection; and I am also aware that Watson, in Patent No. 209,592, has shown a contrivance in the use 20 of which "the mere act of taking up the telephone for use and the replacing or dropping it after use automatically changes the switch to place either the telephone or bell in circuit, or operate the circuit-closing portion to place the 25 telephone in circuit or cut it out of circuit," and I claim neither of these inventions, my invention consisting in a mere mechanical contrivance by which the same lever that operates at any one station, by the transfer of the 30 weight of one of the telephones to place the bell at that station in or out of the circuit, may be made to also throw the telephones of that 35 station into connection with the telephones on either side of that station without connecting them with those on the other side.

The peculiar call-bell of which I make use to illustrate in part the double office of my switch is the subject of another application for a patent of even date, and forms no part of 40 the present invention, except as standing for any ordinary call-bell.

In the drawings, Figure 1 is a front elevation, and Fig. 2 a side elevation, of the instrument used at each of the bell-stations to carry 45 out my invention. Figs. 3 and 4 are sectional elevations of the same. Fig. 5 is a diagram illustrating the different circuits.

A is a wooden table or bracket.

B is a metallic frame secured to the table by 50 screws *a a*, as shown.

C is an electro-magnet secured to the frame B by two screws, *b b*.

D is the bell mounted on the bell-post E, the latter rising between the two spools of the electro-magnet from a cross-bar of the frame 55 B, into which it is screwed.

F is a soft-iron armature swinging on two pins, *c c*, in the frame B, and carrying the bell-hammer H, as shown. A set-screw, *d*, limits the backward play of the soft-iron armature. 60

G is a polarized armature swinging on a pin, *e*, which has bearings in the bell-post, and a bent arm, *f*, extending therefrom, as shown. At the lower end of the polarized armature is a projection, *g*, which stands in the path of the 65 arm of the bell-hammer, or not, accordingly as the current is in one direction or the other.

J is a slot on the under side of the table, across the rear end of which a metallic bar, K, is secured by screws. 70

To the bar K, at *h*, is pivoted a metallic spring-plate, L, having a tongue, *l*, and to the plate L is rigidly secured an insulated metallic hook, M, upon which one of the telephones is to be hung when not in use. 75

N and P are two metallic plates of irregular shape, so secured to the table as to project across the front of the slot J, as shown. The lower edge of each of these plates has a shoulder, as shown, against one or the other of 80 which shoulders the tongue *l* presses by force of the spring-plate L when the telephone is not hung upon the hook M, the tongue *l* being so shaped that it can touch at the same time but one of the plates N or P. The pivot *h*, however, permits the tongue *l* to be turned decidedly to one side or the other, for a purpose to be hereinafter explained. The curved shape of the upper edges of the plates N and P causes the hook M to come to the center and rest upon 90 both plates, thus making metallic connection between the two when the telephone hangs on the hook and overcomes the force of the spring-plate L. When the hook is in this last-named position the tongue *l* is in contact with neither 95 plate N P, and when the tongue is in contact with either plate the hook is in contact with neither.

R is a knob upon the upper end of a rod *r*, the other end of which is rigidly attached to 100 the front end of a spring-plate, S, whose rear end is secured to the table by screws *s s*. The free end of the spring-plate S has a short arm which presses against a metallic pin, *t*, so

driven into the table as to be in contact with one of the screws *w* by which the plate *P* is secured to the table. The connection between the spring-plate *S* and pin *t* may be broken by 5 pressing upon the knob *R*.

O is the lightning-arrester, secured to the front of the table, as shown. It is connected by a wire with screw-cup 3, which, as will be seen hereinafter, has connection with the 10 ground. The apparatus shown has seven screw-cups, marked 1 2 3 4 5 6 7. To avoid confusion in the drawings the wires are not shown in Figs. 1, 2, 3, and 4, but the connections are sufficiently illustrated by the diagram 15 at Fig. 5, where the screw-cups are numbered and other parts lettered, as in the other figures. In addition, *T T* represent the two telephones.

For convenience, I term that part of the line-wire lying on one side of the instrument the 20 "in-wire," and in like manner call the line-wire upon the other side of the station the "out-wire." The in-wire is connected with screw-cup 1, the out-wire with screw-cup 2, and the ground-wire with screw-cup 3, as shown.

25 Screw-cup 1 is connected by a wire with plate *N*, and screw-cup 2 is connected by a wire with one end of the coils of the electro-magnet *C*, the other end being connected by a wire with the spring-plate *S*, which, we have seen, is in 30 metallic connection with plate *P* by means of pin *t* and screw *w*. Screw-cups 4 and 5 are in connection by means of the wires of one of the telephones, and in like manner screw-cups 6 and 7 are connected by the wires of the other 35 telephone, while screw-cups 5 and 6 are connected directly by a wire. Screw-cup 7 is connected by a wire with cross-bar *K*, thus making metallic connection with tongue *l*, through pivot *h* and spring-plate *L*. In the diagram 40 at Fig. 5 this connection between screw-cup 7 and tongue *l* is shown as if by a wire.

The hook *M* being down by weight of the telephone, the electric current, entering at screw-cup 1, passes by wire to plate *P*, screw 45 *w*, pin *t*, spring-plate *S*, to coil *C*, and thence out by screw-cup 2 to the other stations. The circuit is now closed and the bell-hammer rests against the bell, the electro-magnet attracting the soft-iron armature; and this is the situation not only in the instrument shown, but in 50 all similarly-constructed instruments on the line. The bell-hammer may be thrown back and then forward again by breaking and making the circuit anywhere on the line—for example, by pushing down the key *R*. When

the telephone is removed from the hook *M* and the latter is turned to one side, so that the tongue *l* is caught upon the shoulder in plate *N*, the telephones *T T* are in communication with the telephones at the stations on 55 the in-wire, the circuit being from screw-cup 1 to plate *N*, as in the signal-circuit; thence through tongue *l*, spring-plate *L*, by wire, to screw-cup 7; thence through the telephones and cups 6, 5, 4, and cup 3 to ground, thus cutting out all the stations upon the out-wire from screw-cup 2; but if the tongue *l* is caught under the shoulder in plate *P*, the telephones are in communication with the telephones at 60 stations on the out-wire, which enters at cup 2, those on the in-wire being shut out. The circuit is now from screw-cup 2 to the coil; thence through spring-plate *S*, pin *t*, and screw *w*, to plate *P*; thence through tongue *l* to ground, as before—that is, when the telephone 70 is taken from the hook *M* and the latter is moved to the right or left, the tongue *l* catches on the shoulder of the plate *N* or *P*, as the case may be, and the telephone-circuit is established in the desired direction; and no matter upon which side the hook happens to be it is brought to the center and the electric signal-circuit or main circuit established by merely hanging the telephone upon the hook.

I claim—

1. The combination, with a grounded switch and a telephone-support movable with said switch under the weight of a telephone, of contacts connected with the in-wire and out-wire of a telephone-line, and arranged relatively to 80 said switch, as described.

2. The combination, with a spring switch-plate, metallic telephone-support attached to but insulated from said switch-plate, of the contact-plates connected with in-wire and out-wire, and arranged relatively to said switch and support, substantially as described, so that when the telephone is on the support the plates are electrically connected through it, and when the telephone is removed the switch-plate can be brought into contact with either 90 contact-plate, as set forth.

3. The plates *N* and *P*, with shoulders and curved upperedges, substantially as described, for the purpose specified.

GEORGE LEE ANDERS.
